JOHN W. HOGG, JR., OF SCHENECTADY, NEW YORK.

WINDOW-FASTENING.

1,137,321.

Specification of Letters Patent. Patented Apr. 27, 1915.

Application filed September 9, 1913. Serial No. 788,855.

To all whom it may concern:

Be it known that I, JOHN W. HOGG, Jr., a citizen of the United States, residing at and whose post-office address is No. 36 Willow 5 avenue, Schenectady, county of Schenectady, and State of New York, have invented certain new and useful Improvements in Window-Fastenings, and I do hereby declare the following to be a full, clear, and exact description of the invention, such as will enable others skilled in the art to which it 10 pertains to make and use the same.

It is the object of the present invention to provide a window fastener adapted for fastening the sashes together and for securing the sashes to the window casing.

The device is of simple construction and cheap to manufacture, and is so arranged that it need not be made in rights and lefts, 20 but can be used on either side of the window sash at will, simply by reversal of one of the threaded bolts.

In the accompanying drawing, Figure 1 is a perspective view of the fastening in place 25 on the window; Fig. 2 shows the fastening in side elevation.

The fastening may be made from cast metal, iron, brass or the like, but preferably is a drop forging of the shape illustrated in Fig. 30 1; and comprising a platform 1 shaped to fit over the top or meeting rail of the lower sash of a window, and carrying at its outer edge and downwardly extending therefrom a narrow base 2 shaped to fit against the stile of 35 the lower sash. Attachment to the sash may be made by means of screws 3 countersunk flush with the metal, thus making it possible for the device to be attached without the aid of skilled labor.

40 The platform 1 carries a lug 4 integral therewith and centrally positioned on the platform, this lug being drilled and tapped to receive a threaded bolt 5 which carries an integral thumb piece 6, whereby it may be 45 turned easily to advance or withdraw the bolt by turning it in its threaded socket. The bolt can be advanced to seat against the side of the stile 7 of the upper sash, but

preferably it is made to take into sockets 8 formed by drilling into the sash. These 50 sockets may be lined with ferrules to give a finished appearance and to protect them against wear. The base 2 also carries an integral lug 9 forming a socket to support the screw-threaded bolt 10, and this bolt is 55 adapted to seat in holes 11 made in the vertical window stop 12. It will be seen that by withdrawing bolt 10 and inserting it from the other side, the fastening can be changed over from right-hand to left-hand, so that 60 only one type of drop forging need be made.

With the fastening constructed and attached as above disclosed, it is possible to open either the top or the bottom sash of the window and then lock it to the other sash 65 and to the window casing. If desired both sashes may be opened a short distance and at the same time locked against further movement, thus preventing the simultaneous shifting of both sashes to increase the opening above or below. The device can also be used to lock the windows securely when they are entirely closed. It is not unsightly in appearance and does not interfere with the proper manipulation of the window shades, 70 and is free from springs or other delicate parts which might get out of adjustment, and furthermore it has the important advantage that when for a time the locking effect is considered unnecessary, both of the 75 threaded bolts can be retracted far enough to permit free up-and-down movement of the sashes without the need for any attention on the part of the operator, this being a great convenience over any construction 80 having spring bolts which of necessity must be withdrawn when the sash is being raised, 85 having no need for a lock on the window.

What I claim is:

A window fastener comprising a right-angle base adapted to be secured to the top rail and either stile of the lower sash, said base having on its horizontal portion a massive lug and a fastening device associated therewith adapted to engage the stile of the 95

upper sash, the base being extended at either side of said lug to form a flange, and said base having formed integrally and medially of its vertical portion a massive lug extending completely across said vertical portion and having a transversely screw-threaded socket, and a threaded bolt fitting said socket and adapted to engage the window-casing, the bolt being removable and reversible

whereby the fastener is adapted to be applied to either side of the sash.

In testimony whereof I affix my signature, in presence of two witnesses.

JOHN W. HOGG, JR.
